(57) **CLAIM**

The ornamental design for a part of a display screen stand as shown and described.

DESCRIPTION

1.1 : Perspective view in a first position

1.2 : Rear perspective view thereof

1.3 : Front elevation plan view thereof

1.4 : Rear elevation plan view thereof

1.5 : Left side view, right side view is omitted because it is symmetrical to the left side view

1.6 : Top plan view thereof

1.7 : Bottom plan view thereof

1.8 : Enlarged view taken from **1.2**

1.9 : Exploded view

1.10 : Partial enlarged top perspective view in a state of use in an alternate configuration

1.11 : Left side view of another alternate configuration, right side view is omitted because it is symmetrical to the left side view

1.12 : Top plan view of another alternate configuration

1.13 : Rear perspective view in another state of use with additional display screen environment

1.14 : Rear perspective view in another state of use with additional display screen environment

(Continued)

The evenly spaced broken lines indicate portions of the article that form no part of the claimed design. The dot-dash line and adjoining curvy line illustrate the bounds of the enlarged view and form no part of the claimed design.
